UNITED STATES PATENT OFFICE.

DION K. DEAN, OF RAHWAY, NEW JERSEY, ASSIGNOR TO FOSTER WHEELER CORPORATION, OF NEW YORK, N. Y., A CORPORATION OF NEW YORK.

HEAT EXCHANGER.

Application filed March 8, 1926. Serial No. 93,201.

The object of this invention is an improvement in tubular heat exchangers.

In the heating and cooling of certain products, having scaling or corrosive properties, it is desirable to have the tube bundle or heat transmitting surface removable so as to permit substitution of a perfect bundle without undue interruption of service in case the tube bundle in operation in a heat exchanger becomes inoperative for any reason.

This requirement leads to some difficulties in construction since in order to make the tube bundle removable, it is necessary to provide a loose or floating tube sheet with its accompanying liquid chamber entirely within the enclosing shell of the heat exchanger. The fact that there must be a flanging space around the periphery of the space allotted for the insertion of the tubes into the floating tube sheet, to provide for the attachment of the liquid chamber, necessarily makes an unduly large space between the outside of the tube bundle and the containing shell. This permits the short circuiting of a large amount of the fluid flowing outside of the tubes, without being brought into proper contact with the heat transmitting surface.

The object of my invention is to provide means of avoiding this difficulty. In order to explain my invention more clearly, reference is made to Figures 1, 2, and 3 in which like references apply to like parts in all figures.

Figure 1 shows a cross-section of the complete apparatus which is a tubular heat exchanger. A shell "1" is provided at one end with a head "2" and with fluid inlet connection "3" and fluid outlet connection "4". A stationary tube sheet "5" is removably attached to shell "1" at the end opposite to head "2" and furnishes means for attachment of tubes "6" and "7". At the ends of tubes "6" and "7" opposite to stationary tube sheet "5" is provided a floating tube sheet "8" to which is attached bonnet "9", which forms reversing chamber "10" for guiding the flow of fluid leaving tubes "6" into tubes "7". A head "11" with inlet "12" and outlet "13" provides for the entrance and exit of the fluid flowing through tubes "6" and "7". Partition "14" prevents the short circuiting of the fluid entering inlet "12" directly across head "11" and

out through outlet "13" without passing through tubes "6" and "7" dividing head "11" into compartments "16" and "17". Cover "15" closes off the outer end of head "11".

In the apparatus shown for illustrative purposes in Figure 1, it is the intention that the heating fluid shall enter inlet "12" pass through compartment "16" into and through tubes "6" into reversing chamber "10" by which it will be directed into tubes "7" through which it will flow to compartment "17" and out of outlet "13". The cooling fluid preferably would flow through the heat exchanger in a direction countercurrent to the flow of the heating fluid. The cooling fluid passing through inlet "3" would enter the space "18" surrounding tubes "6" within shell "1". In order that its flow shall be countercurrent to the flow of the heating fluid and to prevent the short circuiting of the cooling fluid directly across the spaces "18" and "19" inside of shell "1" directly to outlet "4", longitudinal partition "20" extending completely across the inside of shell "1" is provided. The cooling fluid therefore would be directed through space "18" outside of tubes "7" toward the floating tube sheet "8", would be reversed in flow in space "21" within outer head "2" and would flow through space "19" outside of tubes "6" and out of outlet connection "4". Baffles "22" may be provided for bringing the cooling fluid more intimately into contact with tubes "6" and "7".

Because the floating tube sheet "8" is larger in diameter than the bundle of tubes "6" and "7", there is a space "23" of appreciable dimensions between the tubes "6" and "7" and the inside of shell "1". In order to prevent the short circuiting of the cooling fluid through the space "23" without coming properly into contact with tubes "6" and "7", inner shell "24" is provided. Inner shell "24" fits snugly around the bundle of tubes "6" and "7" and while it may be made up in any manner, a preferable form is shown in Figure 3, which shows a transverse section of the heat exchanger taken at 3-3 in Figure 1.

As shown in Figure 3, inner shell "24" is made up in semicylindrical sections bolted to longitudinal partition plate "20" and may be removable if desired. A packing ring

"25" having some means for making close contact with the inside of shell "1" is provided to prevent the flow of the cooling fluid between the inner shell "24" and the inside 5 of shell "1" through space "23".

Preferably this would be attached rigidly to the inner shell "24" as a flange with a ring of soft packing "26" set in its periphery as shown on a large scale in Figure 2, 10 although I claim as my invention any means for preventing the flow of fluid through space "23". In order to provide the same pressure within and without inner shell "24" a weep hole "27" is provided to permit the space "23" to fill with the fluid 15 circulating in spaces "18" and "19". It will be apparent that while the space "23" will thus be filled and the fluid within it will thus be at virtually the same pressure as the fluid within spaces "18" and "19", no 20 flow of liquid will take place within this space "23" after it is filled.

In this manner I shall with my invention prevent the by-passing of the fluid outside 25 the tubes around the heat transmitting surface without being properly brought into contact with such heat transmitting surface.

While I have shown a tubular heat exchanger arranged for two passes of both 30 the heating and the cooling fluids with a longitudinal baffle and numerous cross baffles, I do not wish to confine myself to this particular type of tubular heat exchanger, but desire to make use of any number 35 of passes for both the heating and the cooling fluid and any number or arrangement of cross baffles in combination with a floating tube sheet. I also retain the privilege 40 of circulating the heating or the cooling fluid inside or outside of the tubes, either in

a concurrent or counter-current manner or in any manner whatsoever.

Having thus described my invention, I claim and desire to secure by Letters Patent—

1. In a tubular heat exchanger, a removable tube bundle, an outer shell, an inner shell closely confining the tube bundle and means for preventing flow of fluid between the inner shell and the outer shell. 50

2. In a tubular heat exchanger, a removable tube bundle, an outer shell, an inner shell closely confining the tube bundle, means for preventing flow of fluid between the inner shell and the outer shell and means 55 for maintaining substantially the same fluid pressure within the space between the inner shell and the outer shell as within the inner shell outside the tubes.

3. In a tubular heat exchanger, a removable tube bundle, an outer shell, a floating tube sheet, an inner shell smaller in diameter than the floating tube sheet and means for preventing the flow of fluid between the inner shell and the outer shell. 60

4. In a tubular heat exchanger, a removable tube bundle, an outer shell, a floating tube sheet, an inner shell smaller in diameter than the floating tube sheet, means for preventing the flow of fluid between the inner shell and the outer shell, and means for maintaining substantially the same fluid pressure within the space between the inner shell and the outer shell as within the inner shell outside the tube. 70

Signed at Rahway in the county of Union and State of New Jersey this sixth day of March, A. D. 1926.

DION K. DEAN.
